United States Patent Office

Des. 195,035

Patented Apr. 16, 1963

195,035

PORABLE OFFICE FILE

Robert K. Fujioka, Los Angeles, Calif., assignor to Lit-Ning Products Company, Beverly Hills, Calif., a corporation of California

Filed Sept. 20, 1961, Ser. No. 66,765

Term of patent 14 years

(Cl. D33—7)

Fig. 1

Fig. 2

Fig. 3

FIG. 1 is a front perspective view of a portable office file showing my new design;

FIG. 2 is an end elevational view of the left side on a reduced scale; and

FIG. 3 is an elevational view of the rear side thereof.

I claim:

The ornamental design for a portable office file, as shown.
